UNITED STATES PATENT OFFICE.

A. BERTSELL IRELAND, OF GREENE, NEW YORK.

CASEIN-MANGLING MACHINE.

No. 801,593.

Specification of Letters Patent.

Patented Oct. 10, 1905.

Application filed July 28, 1904. Serial No. 218,570.

To all whom it may concern:

Be it known that I, A. BERTSELL IRELAND, of Greene, in the county of Chenango, in the State of New York, have invented new and useful Improvements in Casein-Mangling Machines, of which the following, taken in connection with the accompanying drawings, is a full, clear, and exact description.

This invention relates to improvements in machines for mangling casein or curd. This casein or curd is made from the residue of milk after the cream has been separated therefrom and usually consists of irregular-shaped cakes of varying quantities or weight and is usually very tough and rubber-like, so that it is very difficult to disintegrate or mangle.

The object of my present invention is to enable the casein cakes to be quickly and easily shredded or disintegrated into small irregular particles. This is accomplished by means of a rotary mangle and a sliding toothed bar, movable back and forth and across in close proximity to the periphery of the rotary mangle.

Other more specific objects and uses will be brought out in the following description.

In the drawings, Figures 1 and 2 are respectively a top plan and an end view of my improved mangling-machine. Figs. 3 and 4 are sectional views taken, respectively, on lines 3 3, Fig. 1, and 4 4, Fig. 3. Fig. 5 is a plan of the developed surface of the cylinder or rotary mangle, portions thereof being broken away, so as to show several rows of mangling-teeth, this view also showing the position of the teeth of the sliding bar.

Similar reference characters indicate corresponding parts in all the views.

A suitable rectangular supporting frame or base is provided and preferably consists of front, rear, and end walls 1, 2, and 3, which are united to each other to form a rigid open frame or bed, the end walls 3 being provided with suitable bearings 4, in which is journaled a rotary shaft 5, having a driving-pulley 6 at one end and a cam 7 on its opposite end. Mounted upon and secured to the intermediate portion of the shaft is a rotary mangling-cylinder 8, which revolves in the opening in the supporting-frame and is provided with a plurality of pairs of parallel rows of mangling-teeth 9 upon its periphery. I have shown four pairs or sets of these teeth, such sets or pairs being designated by the letters *a*, *b*, *c*, and *d*, and each set is composed of two parallel rows arranged closely together,

but spaced apart circumferentially, and the teeth of each row are also spaced apart axially of the cylinder. These teeth 9 consist of the square heads of suitable bolts which are passed through the shell of the cylinder and are held in place by clamping-nuts on the inner ends of the bolts, as best seen in Fig. 3. A sliding bar 10 of suitable material, as wood, is guided in suitable openings or guides 11 in the end walls 3 beneath but slightly in front of the cylinder 8 and is inclined transversely and tangentially to the periphery of the cylinder and is provided with a row of mangling-teeth 12, which are also square and form the heads of suitable bolts, which are passed through the bar 10 and clamped on its under side by nuts 13. The upper face of this bar 10, adjacent to the periphery of the cylinder 8, is provided with a metal wearing-plate 14, which is held in place by suitable grooves and may be removed when worn and replaced with another plate without removing the bar 10. The teeth 12 are also spaced apart a sufficient distance to permit the teeth 9 to pass through the spaces between the teeth 12. The cam 7 upon the shaft 5 is provided with an annular bearing which is disposed in a plane at an angle other than a right angle with the axis of the shaft 5 and rides between and engages the adjacent faces of a pair of antifriction-rollers 15 on the adjacent end of the bar 10, whereby the rotation of the cam 7 produces a reciprocal motion of said bar 10 back and forth across the face or periphery of the cylinder 8 parallel with the axis of said cylinder.

It is apparent from the construction of the cam that during one-half of its revolution the bar 10 will be moved continuously in one direction a certain distance and during the other half of the revolution an equal distance, so that the maximum throw or movement of the cam—in this instance one inch—is always uniform and continuous from one extreme to the other, and in view of the fact that this bar and the teeth 12 thereon are moved back and forth in the manner described it is necessary to have the teeth 9 of diametrically opposite sets, as the sets *b* and *d*, twisted at a slight angle, or, rather, arranged to conform to the position of different points of the cam during its revolution, as indicated by the line X, Fig. 5, in which it will be seen that certain points of the cam stand at substantially right angles to the bar 10, while other points are disposed at an angle with said bar, and therefore it be-

comes necessary to dispose the heads or teeth 9 in spiral rows circumferentially around the periphery of the drum or cylinder, so that the teeth 9 may always pass between the teeth 12 without friction or clashing with the latter teeth during the reciprocal movement of the bar 10. It is also evident by this peculiar arrangement of teeth on the cylinder and sliding bar and the reciprocal motion of the bar the curd will be cut by one set of teeth at one point, while the next set will cut at a different point, where the former teeth left off, and each set will tear through the curd at different points, thereby traversing the entire body of the curd and insuring a complete disintegration of the cakes a little at a time, but continuously, until the whole cake is torn into particles, this action of the mangling-teeth being produced with comparatively small power on account of the small resistance and shearing effect of the teeth with each other and with the body of the curd.

I have previously stated that the bar 10 was supported in an inclined position transversely at the lower front side of the cylinder 8, and directly in front of the cylinder and bar 10 is an inclined table 16, which is disposed in substantially the same plane as the upper surface of the bar 10 and is provided with a series of V-shaped ribs 17 on its upper face, which serve to guide the body of curd and to permit it to feed by gravity between the cylinder 8 and bar 10. This table is also provided with side walls 17' to keep the curd within the bounds of the mangling-cylinder 8 and bar 10, the outer or upper end of the table being adjustably secured to suitable brackets 18, rising from the supporting bed or frame and provided with suitable slots 19 for receiving clamping-bolts 20, these clamping-bolts being passed through the sides 17' for securing the table in its adjusted position, the lower end of said table being adjustable by a suitable screw 21, as best seen in Fig. 3.

In the operation of my invention the body of the casein or cake of curd is placed by hand upon the inclined table 16, along which it gravitates or may be fed by hand between the cylinder 8 and the upper face of the bar 10, where it is caught by the revolving teeth 9 and sheared against the teeth 12, thus removing or tearing small particles of the curd from the main body as each row of teeth 9 is successively presented to the teeth 12, or rather as the teeth of each row pass between the teeth 12. The movement of the bar 10 is governed by the cam 7, and therefore by arranging the teeth 9 circumferentially around the cylinder in a plane parallel with the cam it is evident that by rotating the cam and cylinder together the movement of the bar 10 is timed so that the spaces between its teeth will be brought into position to permit the teeth 9 of each row to pass successively between the teeth 12, thus traversing and cutting the entire body of curd

as it is fed between the mangling-cylinder 8 and bar 10. This will be better understood upon reference to Fig. 5, in which I have shown the teeth of the bar 10 in four different positions to which it is brought by the cam 7 during one complete rotation of the cylinder and cam, these positions being assumed as each set *a*, *b*, *c*, and *d* of the teeth 9 are successively brought into registration with the teeth 12 of the bar 10. In this Fig. 5 in the first row (marked *a*) the teeth 12 are indicated in the extreme position to the left as effected by one position of the cam 7. Now when the cam is rotated a quarter of a turn or the distance between one set of teeth and the next succeeding set, as from *a* to *b*, the bar 10 will have been moved one-half inch, providing the cam has an inch throw, or to the position seen at *b*, Fig. 5. In the position seen at *a* one row of that set has just passed between the teeth 12 and the other row is just about to pass between the said teeth 12, and at this point the cam stands nearly at right angles to the bar, while at the position *b*, Fig. 5, the cam stands at an angle and the teeth 9 of the set *b* are therefore disposed at an angle. As the set *c* is brought to the teeth 12 the bar will at this time have moved to its extreme position to the right, and the teeth of the set *c* are therefore arranged to pass between the teeth 12 of the bar when in this position. The cam 7 now begins to return the bar to its first position, and when the set *d* of the teeth 9 are brought into registration with the teeth of the bar 10 the cam 7 will have drawn said bar back one-half of its movement, so that when the complete revolution of the cylinder and cam is made by the return of the set *a* of teeth, as seen at the bottom of Fig. 5, the cam will have returned the bar 10 and its teeth to the starting position.

It will be observed upon reference to line *x*, Fig. 5, which is the developed line of one circumferential row of teeth 9 and also the developed line of all points in the cam that the points in line opposite to the sets of teeth marked *b* and *d* are at an angle with the axis of revolution of the cam and cylinder, while the extreme points at *a* and *c* are perpendicular to the axis and bar 10, and therefore the teeth of the sets *a* and *c* are arranged parallel with the line of rotation, while the teeth of the sets *b* and *d* are disposed at an angle with the line of rotation.

It is believed that this description is sufficiently clear to enable any one skilled in the art to make and construct this machine.

Having thus described my invention, what I claim, and desire to secure by Letters Patent, is—

1. In a casein-mangling machine, a rotary mangler and reciprocating mangler both having intermeshing teeth operating together to mangle the casein between them, said manglers being connected to move together.
2. In a casein-mangling machine, a rotary

mangler and a reciprocatory mangle movable axially of the rotary mangle, both parts having intermeshing teeth operating together to disintegrate the casein between their contiguous faces, means to feed the casein between the manglers, and means connected to drive said parts.

3. In a casein-mangling machine, a rotary cylinder having teeth in its periphery, a sliding bar traveling across the face of the cylinder and also provided with teeth intermeshing with those of the cylinder to disintegrate the casein, and means rotating with the cylinder and connected to drive said bar.

15 4. In a casein-mangling machine, a rotary cylinder having a plurality of rows of teeth on its periphery, a sliding bar movable across the face of the roller and provided with teeth intermeshing with those of the cylinder to disintegrate the casein, and means connected to actuate the cylinder and bar at the same time.

5. In a casein-mangling machine, a rotary cylinder having teeth on its periphery, a driving-shaft for the cylinder, a cam on the shaft, 25 and a bar actuated back and forth across the face of the cylinder by said cam and provided with mangling-teeth intermeshing with the teeth of the cylinder to disintegrate the casein.

6. A casein-mangling machine comprising 30 a sliding bar having teeth spaced apart, a rotary annular bearing disposed in a plane at an angle other than a right angle with its axis, bearings on the bar engaged by said ring whereby the bar is reciprocated axially of the 35 cam, a cylinder rotating on the same axis with

the cam and having teeth riding between the teeth on the bar.

7. A casein-mangling machine comprising a rotary cylinder having teeth spaced apart axially and spirally around its surface, a feeding-table inclining upwardly and tangentially from the lower portion of the cylinder, a bar in substantially the same plane as and at the lower edge of the table and provided with a row of teeth, a rotary cam connected to the 40 bar to slide it edgewise as the cylinder rotates and so timed with reference to the movement of the cylinder that successive teeth of one part pass between the teeth of the other part, and means to rotate the cylinder and cam. 50

8. A casein-mangling machine comprising a rotary shaft, a cylinder on the shaft, a plurality of rows of teeth on the periphery of the cylinder, the rows being spaced apart circumferentially, and the teeth of each row spaced apart axially of said cylinder, a bar slidable back and forth across the face of the cylinder and provided with a row of teeth spaced apart axially of the cylinder, the teeth of the cylinder and bar passing between each other, a 55 cam on the shaft connected to operate the sliding bar, and an inclined table along which the casein is fed by gravity between the bar and cylinder.

In witness whereof I have hereunto set my 60 hand this 21st day of July, 1904.

A. BERTSELL IRELAND.
